TRANSCRIBING ADAPTOR OR SIMILAR ARTICLE

Peter Quay Yang, New York, N.Y., assignor to The
Gray Manufacturing Company, a corporation of
Connecticut

Filed June 4, 1968, Ser. No. 12,206

Term of patent 14 years

U.S. Cl. D26—14
Int. Cl. D14—01

FIG. 1

FIG. 2

FIG. 3

FIG. 4

FIG. 5

FIG. 6

FIGURE 1 is a perspective view of a transcribing adaptor or similar article showing the front, top and left end of my new design;

FIGURE 2 is a top plan view;

FIGURE 3 is a front elevational view;

FIGURE 4 is a rear elevational view thereof;

FIGURE 5 is a left end elevational view; and

FIGURE 6 is a right end elevational view.

I claim:

The ornamental design for a transcribing adaptor or similar article, as shown.
